UNITED STATES PATENT OFFICE.

CLYDE L. CRAIG, OF WASHINGTON COURT HOUSE, OHIO.

LATCH.

1,201,940.

Specification of Letters Patent. Patented Oct. 17, 1916.

Application filed March 23, 1916. Serial No. 86,061.

To all whom it may concern:

Be it known that I, CLYDE L. CRAIG, a citizen of the United States, and a resident of Washington Court House, in the county 5 of Fayette and State of Ohio, have invented a certain new and useful Improvement in Latches, of which the following is a specification.

My present invention relates generally to 10 latches, and more particularly to a latch for connecting members to be joined, of a nature adapted to clamp the members tightly together in firm even contact and which may be readily and quickly manipulated to either 15 clamped or released position.

A further object of my invention is to provide a latch of the above type capable of general application in connection with parts to be connected, such as for instance, doors, 20 gates, and others, and capable of effective use wherever adapted.

In the accompanying drawing illustrating several forms of which my invention is susceptible, Figure 1 is a perspective view illustrating the practical application of my improved latch in connection with barn doors. Fig. 2 is a detail perspective view of the latch member in clamped position. Fig. 3 is a detail horizontal section taken substantially on line 3—3 of Fig. 2. Fig. 4 is a detail vertical section taken substantially on line 4—4 of Fig. 3. Fig. 5 is a fragmentary elevation of the inside portion of connected doors, as seen in Fig. 1. Fig. 6 is an elevation illustrating my invention applied in connection with swinging doors. Fig. 7 is a view partly in elevation and partly in section illustrating the latch as shown in Fig. 6, in clamped position. Fig. 8 is a detail 35 perspective view illustrating my improved latch utilized for connecting a gate, for instance, with a gate post, the latter forming one of the members to be connected. Fig. 9 is a detail perspective view illustrating two 40 members to be connected, in detached relation, one of said members having certain means constituting a slight modification of the form shown in Fig. 7. Fig. 10 is a detail perspective view illustrating the application 45 of my invention to automobile and like vehicle doors. Fig. 11 is a side view of the parts shown in Fig. 10.

Referring now to the figures, and more particularly to the form as illustrated in 50 Figs. 1 to 5, inclusive, the two members 10

and 11 to be connected may be, as shown, of angular form, one of their flanges being secured to the battens 12 of barn doors 13 or like doors of a sliding nature, by means of bolts or other fastening members 14, and 60 the other flange thereof having slotted openings 15 through which the laterally extended head 16 of my improved latch piece is adapted to be projected said head being, as shown, elongated in one direction and having inclined inner faces 17 as best seen in Fig. 3, whereby when inserted through the slots 15, turning movement of the head to a position at right angles with respect to the slots, 65 serves to draw the meeting flanges of the 70 members 10 and 11 tightly together in firmly and evenly clamped relation. In this form of the invention, the head 16 is secured in connection with a handle member 18 at a point intermediate the ends of this handle 75 member, which passes through the member 11 and through the respective door 13, and is provided with angular portions 19 upon relatively opposite sides of the door, the head 16 and the handle member 18 being so 80 disposed in relation to one another that when the head 16 is in the clamped position shown in Fig. 2, the inner angular portion 20 of the handle member may be lowered 85 into a recessed portion 21 on the inner face 85 of the respective door 13, so as to obviate interference with the door frame or the adjacent parts of the building when the doors are opened.

The form of the invention shown in Figs. 90 6 and 7 illustrates the manner in which the invention may be used with particular success in connection with sagging doors of the hinged type, the members 23 and 24 to be connected being secured to the meeting edges 95 of the doors, or those edges supposed to meet, as seen in Fig. 6, these members to be connected being provided with flanges 25, as seen in Fig. 7, provided with elongated slots 26 through which the laterally extended head 27 is projected, its inner inclined edges 28 serving to clamp the flanges 25 firmly and evenly together, in latched position, as shown in Fig. 7, so as to draw the doors 100 closely together into non-sagging relation. In this form of the invention, the head 27 is shown as mounted at one end of a handle 29, the opposite end of which may be attached by a chain 30 to one of the doors 32, 105 in order to prevent loss of the latch piece 110

which, as seen, is wholly detachable from both of the members 23 and 24 to be connected.

The form of the invention shown in Fig. 9 differs from that shown in Figs. 6 and 7 just above described, in that a guard plate 31 is secured to the member 24 to be connected in order to movably confine the handle 29 and thus prevent loss of the latch piece, 10 so as to dispense with the use of a chain, such as shown at 30, in Figs. 6 and 7.

In Fig. 8 the latch piece 32 of the same construction as previously described in connection with Figs. 6 and 7 is utilized in connection with members to be secured, one of which is a plate 33 attachable, as for instance to a gate, and the other of which may be a gate post, as seen at 34, having a slotted opening to align with the slotted opening 35 of one flange of the plate 33, and thus provide for the entrance and operation of the laterally extended head of the latch piece.

In the form of the invention shown in Figs. 10 and 11 the latch piece is confined in connection with the door carried plate 36, its laterally extended head 37 being adapted for engagement through the recess 38 of a recessed keeper 39 secured to the body 40, the handle 41 of the latch piece being preferably controlled by a spring 42 hinged to maintain the head 37 in position at all times. In order to effect automatic engagement of the head 37 through the recess of the keeper in this form of the invention, the outer face of the head is also inclined, as particularly seen in Fig. 11, so that upon forcible contact with the keeper, the head will be restricted to a position permitting of its passage through the recess 38 and will thereafter be drawn to latched position by the spring 42.

It is obvious therefore that I provide a latch especially effective in securely clamping in firm even contact, parts to be connected, and capable of various uses, as illustrated and described. It is obvious further that I provide a latch, the latch piece of which may be readily and quickly manipulated, both to latched and released position.

In the forms of the invention shown in Figs. 1 to 7, inclusive and 9, the meeting flanges of the members to be connected may also be provided with apertures as indicated at 43, which align when the parts are clamped together, so as to receive the shackle of a padlock 44, as seen in Fig. 2, for the purpose of locking the parts so clamped and connected, against unwarranted manipulation and entry.

It is to be understood that the non-sagging feature, or rather, the adaptability of my invention to the drawing together and firm clamping of sagging doors, in even non-sagging relation is an important fea-

ture of the invention and a great advantage over other door latches. By this means sagging doors can be readjusted and raised to their proper positions, at which point it has been found by experience they will swing, eliminating the disagreeable feature of the doors dragging on the floors as shown in Fig. 6.

I claim:

1. In a latch, the combination with parts to be connected, of a pair of angular members secured thereto, having portions to be clamped extending at right angles to the parts to be connected and provided with slotted openings, and a lever swingable toward and away from the parts to be connected, having a laterally projecting head spaced from a portion of the lever for engagement through said openings, said head being elongated in one direction and provided with inclined faces at the inner sides thereof.

2. In a latch, the combination with parts to be connected, of a pair of angular members secured thereto, having portions to be clamped extending at right angles to the said parts to be connected and provided with slotted openings, and a lever swingable toward and away from the parts to be connected, having a laterally projecting head for engagement through said openings, said head being elongated in one direction and provided with inclined faces at the inner sides thereof, and a guard plate secured to one of said members and overlying the headed portion of the lever whereby to movably confine the latter in connection with the said member.

3. In a latch of the type described, a pair of members to be clamped provided with portions having slotted openings, and a latch piece including a laterally extended head elongated in one direction and provided with inclined faces at the inner sides thereof, and a lever intermediate the ends of which said head is mounted, said lever extending through one of the said members and swingable in a plane parallel to the slotted portion of said member, and said lever having angular handle portions upon relatively opposite sides of the said member.

4. In a latch of the type described, the combination with doors to be connected, one of which is provided with an elongated slot parallel with and adjacent its free edge, and with a transverse recess in its inner face, of a pair of angular members to be connected, secured to the doors adjacent their meeting edges and provided in their outstanding flanges with elongated slots, one of said members having a slot in alignment with the slot of the respective door, and a latch piece including a laterally extended head elongated in one direction and provided with inclined faces at the inner side thereof,

and a lever intermediate the ends of which said head is mounted, said lever extending through the door slot and the slot of the last mentioned member to be connected 5 aligned therewith and swinging parallel to the free edge of the door, and said lever having angular handle portions upon relatively opposite sides of the door, the angular portion at the inner side of the door being movable into said recess of the door and into 10 countersunk relation thereto, all substantially as and for the purpose described.

5. In a latch, the combination with mem- bers to be clamped having slotted portions, and a lever swingable toward and away 15 from said members, having a handle and having a laterally extended head projectable through the slots of said members and elongated in one direction, and having inclined faces at the inner sides thereof, said lever 20 having a reduced stem at one side connecting the same with the said head and extending through the slot of one of said members to form the pivot of swinging movement of the lever.

CLYDE L. CRAIG.
